(57) **CLAIM**

I claim the ornamental design for a wireless charge cradle for electrical devices, as shown and described.

DESCRIPTION

FIG. 1 is a top front right perspective view of a wireless charge cradle for electrical devices.

FIG. 2 is a top rear right perspective view thereof.

FIG. 3 is a rear elevational view thereof.

FIG. 4 is a front elevational view thereof.

FIG. 5 is a top plan view thereof.

FIG. 6 is a bottom plan view thereof.

FIG. 7 is a right side elevational view thereof; and,

FIG. 8 is a left side elevational view thereof.

The broken lines shown in the drawing illustrate portions of the article that form no part of the claimed design.
